APPARATUS FOR KNITTING

Herman Fuchs, Colmar, Pa.

Application March 11, 1933, Serial No. 660,418

5 Claims. (Cl. 66—109)

My invention is an improved apparatus for knitting fabrics, particularly on full fashioned knitting machines in which reciprocating thread carriers lay threads along a row of sinkers which are then moved between alternate needles to form loops. The loops are subsequently subdivided by the movements of usual dividers and the smaller loops are discharged from the sinkers and dividers onto knock-over bits by which such loops are held while the needles are drawing down such new course of loops through the previously formed loops of the fabric.

In order to obtain uniform stitches in such fabrics, it is desirable that the yarn forming the new course of loops be held under substantially uniform tension from the time such loops are formed by the sinkers and dividers until they are knitted through the loops of the preceding course, so as to avoid any distortion in the size or shape of the respective loops from the time they are formed until their knitting into the fabric is completed. Such distortion in the size and shapes of the loops commonly results from failure to elevate the knock-over bits sufficiently high to maintain the tension on the yarn after the loops are discharged from the sinkers and dividers, or from failure to draw down the needles immediately upon the discharge of the loops onto the knockover bits. If, however, the loops are subjected to excessive tension or stress by movement of the needles downward before the usual cam mechanism effects the corresponding movement of the knock-over bits, the yarn is likely to be stretched and broken or the needles bent or broken, with consequent irreparable damage to the fabric.

In accordance with my invention, the knock-over bits are yieldingly supported so as to permit slight relative movement between the knock-over bits and the cam mechanism by which they are operated. This yielding support elevates the knock-over bits above the positions to which they are normally elevated by their cams and to positions substantially level with the discharge ends of the sinkers and dividers, so that there is substantially no change in the tension imposed by the needles on the yarn loops in the movement thereof from the sinkers and dividers onto the knock-over bits. The breakage of the yarn or needles, on the downward movement of the latter, is prevented by the yielding of the knock-over bits to a limited extent before they are moved downward by the cam mechanism for operating the same, and any irregularity in the movement of the knock-over bits induced by the

cam mechanism is compensated for by the expanding action of the yielding support. Consequently, I maintain the yarn under a substantially uniform tension and in loops of uniform size during the knitting operation.

The characteristic features and advantages of my improvements will further appear from the following description and the accompanying drawing of illustrative embodiments thereof.

In the drawing, Figure 1 is a fragmentary perspective view of a section of a full fashioned knitting machine having knock-over bits supported in accordance with my invention; Figure 2 is a diagrammatic transverse sectional view of a full fashioned knitting machine having my improvements applied thereto; Figure 3 is an enlarged side elevation, partly in section, showing one form of yielding support for the knock-over bits; and Figure 4 is a front elevation illustrating diagrammatically a second form of yielding support for knock-over bits of a type of full-fashioned knitting machine commonly known as the German type of knitting machine.

As illustrated in Figures 1 to 3 of the drawing, a full fashioned knitting machine, of known type, is provided with a thread carrier 1 which lays yarn under tension from a suitable source of supply upon sinkers 2, operated by a usual slur cock, to form loops around needles 3, which loops are sub-divided by dividers 4, operated by a usual form of catch bar. The needles 3 are mounted upon a usual form of needle bar, which is operated by a usual type of cam mechanism to first move the needles 3 downwardly so that their beards overlap the loops formed by the sinkers and dividers; then move the needles inwardly against the press-bar 6 to close the beards; then move the needles outwardly to the ends 2' of the sinkers 2 and ends 4' of the dividers 4; and then move the needles downwardly to knit the loops thereon through the previous course of loops.

When the needles 3 have moved the loops outwardly to the ends 2' of the sinkers and 4' of the dividers, the old loops are cast off onto the knock-over bits 7, which are mounted upon a knock-over bar 8 having journals journaled in bearings supported by the frame of the sinker head. The knock-over bar 8 has connected therewith a link 10, which has pivotally connected therewith a link 11 having at the end thereof an elongated seat by which it is journaled on a bearing 12 of the lever 13 fulcrumed on the bearing 14. The seat in the rod 11 for the bearing 12 is substantially greater in width than the

5 diameter of the bearing 12, and a pin 15 is reciprocal in the arm 11 and normally pressed outwardly against the bearing 12 by a spring 16. The thrust of the spring 16 through the mechanism described causes the movement of the knock-over bits 7 to an elevated position adjacent to the ends of the sinkers and dividers when the knock-over bar is moved to its upper position.

10 The lever 13 is pivotally connected by a link 17 with a lever 18, which is rocked through a roller 19 by the cam 20 on the main cam shaft 21 of the machine.

15 It will be understood that when the needles are about to move the loops from the sinkers and dividers onto the knock-over bits 7, the high point of the cam 20 engages the roller 19 and acts through the intermediate lever mechanism to elevate the knock-over bar to its highest 20 position, and the knock-over bits are held in their highest position adjacent to the sinkers by the spring 16. As the loops are discharged onto the knock-over bits 7, the needle bar is moved downward, drawing with it the needles 3 and the loops thereon. This movement pulls the 25 knock-over bits downwardly against the yielding action of the spring 16 before the rotation of the cam 20 permits sufficient movement of the roller 19 and connected lever mechanism to move the knock-over bar 8 downwardly. After the nose of the cam 20 has passed beyond the roller 19, so as to permit the downward movement of the knock-over bar 8, the spring 16 tends to expand so as to maintain a constant 30 tension on the loops until they are drawn from the knock-over bits and knitted into the preceding row of loops of the fabric.

35 As illustrated in Figure 4, my invention may be applied to a full-fashioned knitting machine having a vertically reciprocating knock-over bar 8a containing recesses 8b for the reception of operating rods 8c mounted on a shaft 8d from which movement is transmitted to the knock-over bar and bits through yielding springs 8e.

40 Having described my invention I claim—

45 1. In a knitting machine, the combination with a loop-forming mechanism, and knock-over bits cooperating therewith, of operating mechanism for the bits including a lever having a longitudinal bore communicating with a pivot-end slot, a second lever, a bearing in said slot pivotally connecting said levers, a plunger in said bore, and a spring in said bore biasing the plunger against said bearing.

50 2. In a full-fashioned knitting machine, the

5 combination with sinkers and a movable bar carrying knock-over bits adjacent to said sinkers, of means for operating said bar including a yielding connection having a bearing with spaced bearing surfaces and a member movable between said bearing surfaces, and a device biasing said member toward one of said bearing surfaces.

10 3. In a full-fashioned knitting machine, the combination with sinkers, a movable bar carrying knock-over bits co-operating with said sinkers and means for operating said bar including a yielding connection comprising a slotted member having bearing surfaces at the ends of said slot, a second member movable in said slot between said surfaces and a compression spring carried by one of said members and biasing said second named member toward one of said bearing surfaces.

15 4. In a full-fashioned knitting machine, the combination with sinkers and a movable bar carrying knock-over bits cooperating with said sinkers, and means for operating said bar and including a rocking member, a second member having a bearing surface having a fixed relation 20 to said knock-over bits and a biasing device biasing said knock-over bits upward, said rocking member engaging said bearing surface and elevating said knock-over bits to their normal position on compression or failure of the biasing 25 device, and said rocking member otherwise engaging said biasing device and elevating said knock-over bits beyond the normal elevation to which they are movable by the engagement of said member with said bearing surface.

30 5. In a full-fashioned knitting machine, the combination with sinkers and a movable bar carrying knock-over bits cooperating with said sinkers and a cam for elevating said knock-over bits to normal upward position relative to said 35 sinkers, and a lever train through which said knock-over bits are operable by said cam and a biasing device by which said knock-over bits are biased, said lever train including bearing surfaces positively engageable to move said knock-over bits to normal upward position upon compression or failure of said biasing device, and the movement imparted to the lever train by the cam being otherwise transmitted through the biasing device and elevating the knock-over 40 bits above the positions to which they are movable by said cam through the directly contacting 45 bearings of said lever train.
